UNITED STATES PATENT OFFICE

ALBERT L. SOTHEN, OF CHICAGO, ILLINOIS

SHOE ATTACHMENT

Application filed December 17, 1927. Serial No. 240,893.

This invention relates to certain novel improvements in shoe attachments and is particularly adapted to a construction which provides a rigid sole for the shoes of dancers and the like.

The salient object of my invention is to provide a stiffening member for the sole portion of a dancer's shoe which will act to strengthen the shoe so as to prevent bending 10 of the sole portion thereof and which will therefore reduce the fatigue of tap dancers and the like.

Another object of the invention is to provide a rigid sole for dancers' shoes preferably 15 composed of metal such that when a tap dance is being performed a distinct sound will be provided as the dancer's feet touch the floor.

A further object of the invention is to provide 20 a stiffening member for shoe soles which will be mounted thereon in such a manner that the pulling of the securing elements by the extraordinary stresses placed thereon will be obviated.

A still further object of the invention is to provide 25 a device of the foregoing character which will be economical in construction and which will be formed so as to be light in weight.

Other objects will appear hereinafter.

The invention consists in the novel combination and arrangement of parts to be hereinafter described and claimed.

The invention will be best understood by 35 reference to the accompanying drawings, showing the preferred form of construction and in which;

Fig. 1 is a side elevational view of a shoe to which my improved stiffening member has 40 been attached;

Fig. 2 is the plan view of a preferred form 45 of construction for my improved stiffening member;

Fig. 3 is a partially longitudinal sectional view of my improved stiffening member attached to a dancer's shoe; and

Fig. 4 is a sectional view taken on the line 4-4 on Fig. 2.

In the drawings wherein I have illustrated 50 a preferred form of construction for my in-

vention it may be seen that I provide a rigid body member 10 preferably composed of metal which is shaped so as to correspond to the sole portion of a shoe; that is, the toe portion thereof is formed as indicated at 55 11 and the side portions thereof are formed so as to be substantially similar to the side edges of the sole of a dancer's shoe. As is best illustrated in Fig. 2 the center portion of the body 10 is cut away as at 12 so as to reduce the weight thereof and also to reduce friction. A plurality of openings 13 are provided in the body 10 which are preferably arranged in the manner shown in Fig. 2.

As is best illustrated in Fig. 1 the body 10 is secured to sole 14 of a dancer's shoe 15 by inserting suitable securing elements such as the screws 16 or tacks through the openings 13 and into the sole 14 of the shoe. The body 10 is of such a length that it terminates 60 forwardly of the instep portion of the shoe so that the shoe may be bent without interfering with the stiffening member 10. This inward edge 17 of the body 10, which is juxtaposed to the instep portion of the shoe, curves 65 inwardly so that the innermost portion of the arc thereof is disposed substantially on a longitudinal center line of the body 10 so as to define projecting ears 18 and 19. These 70 projecting ears 18 and 19 are located on the shoe sole 14 at the point where wear and friction will be greatest especially during the execution of certain dance steps such as, for example, wing steps and thus the life of the 75 stiffening member will be prolonged. Since the body member 10 ends at a point disposed forwardly of the bending portion of the shoe sole, it is apparent that the strain impressed upon the securing elements 16 will be reduced 80 to a minimum and thus undesired displacement of the stiffening member will be prevented.

As is best illustrated in Fig. 4 the transverse shape of the body member 10 is convex 85 so as to correspond to the configuration of an unused shoe sole. Therefore the stiffening member 10 will tend to retain the shoe in its original shape, that is so as to be convex transversely as well as convex longitudinally as indicated in Fig. 3. Therefore the highest 90

point in the shoe sole will be at substantially the mid portion thereof at which point the opening 12 is disposed and thus friction will be reduced at this point. It is apparent that this double convex formation and the opening will reduce friction when steps such as so called right and left wing steps are executed at which time the action will center on either the right or left edge of the sole and 10 the body member 10.

The foregoing construction provides a stiffening member for shoe soles which will be particularly advantageous for dancers and especially for so called tap dancers, for inasmuch as the body 10 is composed of metal, it is apparent that as the dancer's feet strike, a distinct sound will be produced which will be conducive to a pleasing effect. To augment this condition I also provide a body 20 which 15 may be secured to the heels of the shoes. The inner edge of the body 20, disposed toward the instep portion of the shoe, is formed substantially similar to the inner edge of the body 10 so as to produce outstanding lugs or 20 ears which will serve in a manner substantially similar to that described for the ears 18 and 19. The heel covering body members 25 20 are convex transversely but the longitudinal curvature is not required.

30 It is apparent from the foregoing description that I have provided an advantageous construction for dancers' shoes which will act to stiffen the sole portions thereof and which will also add life to the sole portions and will 35 act similarly when attached to the heel portions. The construction as described provides additional material at the points of greatest wear so as to prolong the life of my improved device. Further, the device as described will 40 permit bending of the dancer's foot at the ball portion thereof. As stated, the device is so mounted that such bending will not displace the body 10 from the sole portion of the shoe.

45 While I have illustrated and described the preferred form of construction for carrying my invention into effect, this is capable of variation and modification, without departing from the spirit of the invention. I, therefore, do not wish to be limited to the precise 50 details of construction set forth, but desire to avail myself of such variation and modifications as come within the scope of the appended claim.

55 Having thus described my invention, what I claim as new and desire to protect by Letters Patent is:

In combination with a shoe sole, a metallic stiffening member having openings therein, 60 securing means inserted through said openings for fastening said member to the sole, said member having a formation substantially similar to the sole and having the inner transverse end thereof disposed forwardly of 65 the flexing portion of the sole, said member

having ears extending outwardly from said inner end to the flexing portions of the sole and having openings in said ears through which securing elements may be inserted, said member including transversely and longitudinally extending convex formations arranged so that the peaks of said formations will tend to converge at substantially the midpoint of said member, said member having an enlarged opening at said midpoint to remove the portion of said member in which 70 said curved formations would converge.

75 In testimony whereof I affix my signature.

ALBERT L. SOTHEN.
